STRAP ASSEMBLING APPARATUS

Harry Alfandre, Jamaica, N. Y.

Application August 27, 1946, Serial No. 693,347

18 Claims. (Cl. 223—49)

1

This invention relates to apparatus for assembling buckles and tapes in the manufacture of adjustable straps of the type commonly used in ladies' undergarments, for instance.

One well known type of adjustable strap of this type comprises two separate tapes and a single buckle having several openings through which the tapes are looped. Looping the tapes through the buckle by hand is a tedious and time-consuming task, particularly since one of the tapes has to be looped repeatedly through the buckle. Hence, manual assembly of the buckle and tapes does not lend itself to efficient mass production of adjustable straps.

It is the primary object of the present invention to provide apparatus in which buckles and tapes are rapidly assembled into adjustable straps of the type referred to, without requiring any special skill on the part of the operator of the apparatus.

The above and other objects, features and advantages of the invention will be more fully understood from the following description, reference being had to the accompanying illustrative drawings.

In the drawings:

Fig. 1 is a fragmentary perspective view, partly broken away, of apparatus embodying the present invention;

Fig. 2 is a perspective view of a prominent part of the apparatus;

Fig. 3 is a fragmentary, part-elevational and part-sectional view of the apparatus;

Fig. 4 is a bottom view of part of the apparatus as viewed in the direction of the arrow 4 in Fig. 3;

Fig. 5 is a section taken substantially on the line 5—5 of Fig. 1;

Fig. 6 is a detail view of a buckle;

Fig. 7 illustrates a special holder carrying a supply of buckles to be transferred to the apparatus;

Figs. 8 to 11, inclusive, diagrammatically illustrate certain steps in the operation of the apparatus; and

Fig. 12 shows a finished adjustable strap of the type referred to.

Referring to the drawings, and particularly to Figs. 1 and 3 thereof, the reference numeral 20 designates the base of the apparatus which may be suitably mounted on a bench or other support 22. Mounted on, or integral with, the base 20 is a block 24 having forwardly projecting, spaced legs 26 (Figs. 1, 3 and 5) which extend beyond the base 20. Slidable in a bore 28 in the block 24

2

is the cylindrical shank 30 of a slide 32 which is guided for linear movement between the legs 26 of the block 24 by ribs 34 on said legs (Fig. 5). An intermediate portion of the shank 30 of the slide is threaded as at 36, and the adjacent reduced end of said shank is slidable through a guide lug 38 on the base 20. The threaded portion 36 of the shank of the slide extends through an arm 40, and the latter is held longitudinally adjustable on said shank by means of nuts 42 (Fig. 1). The arm 40 is connected by a link 44 with a bell-crank lever 46 which is pivotally mounted at 48 on a depending bracket 50 on the base 20. A link 52 connects the bell-crank lever 46 with a foot pedal (not shown) which, on being depressed by the foot of the operator of the apparatus, causes the advance of the slide 32 from the most retracted or home position shown in Figs. 1 and 3 into a most advanced position to be described. The bell-crank lever 46 is normally urged by a spring 54 into the position shown in Figs. 1 and 3, in which the slide 32 is in its most retracted position.

Bolted or otherwise secured to the top of the spaced legs 26 of the block 24 is a bracket 58 (Fig. 1) on which is suitably mounted an upright magazine or rack 60 of the T-shaped cross-section shown in Fig. 2. The rack 60 serves for the storage of a stack of identical buckles 62 of the type best shown in Fig. 6. Buckles of this type are preferably made from flat stock of metal, plastic or any other suitable material, and each buckle is provided with several elongated tape-receiving slots 64 of which one is accessible from the adjacent edge of the buckle through a transverse slot 68. As shown in Fig. 2, the rack 60 projects into the transverse slots 68 and communicating longitudinal slots 64 of the stacked buckles 62, and the latter are slidable on said rack and held thereby in their stacked relation. A supply of buckles of this type may, prior to their placement on the rack 60 be stacked, on a special holder 70 (Fig. 7) by passing the latter through identical slots 64 of said buckles. The holder 70 may be in the form of a strip of cardboard or any other suitable inexpensive material into which wire staples may be driven. Conveniently, wire staples 72 are driven through the ends of the strip 70 to retain the stacked buckles 62 thereon. The rack 60 is loaded with buckles by cutting off the lower end of the strip 70 with the staple or staples 72 thereon (Fig. 7), and permitting the buckles 62 on said strip to gravitate onto said rack while holding the severed end of the former 55 in alignment with the top end 60' of the latter.

In this way, the rack 60 forms a continuation of the strip 70 and the buckles 62 on the latter slide directly onto the rack when leaving the strip.

The forward end of the slide 32 is cut away at 74 (Figs. 1 and 3) to form a shoulder 76 with which to advance a buckle in a track 78 from adjacent the discharge end 60' of the rack to an assembly station A (Fig. 3). The track 78 is formed by grooves 79 in the adjacent edges of cooperating clamping jaws 80. One wall of each of the grooves 79 is machined away as at 81 (Figs. 1 and 3) so as to admit a buckle from the rack 60 into the track 78. The side walls of the guide grooves 79 in the jaws 80 adjacent the rack discharge end 60', which are flush with the cut-away end 74 of the slide 32 (Fig. 3), are so spaced from said rack discharge end that only the lowermost buckle on the rack may descend into the track 78 and clear the rack, while all the other buckles on the rack are held on the latter. Hence, the rack 60 permits the gravity discharge of one buckle at a time into the track 78.

Preferably, one of the jaws 80 is fixed, and the other jaw is pivotally mounted at 84 on the block 24 and normally urged toward its companion jaw by a spring 86 which is anchored at 88 on the bracket 58. The yielding jaw 80' (Fig. 1) is normally urged into engagement with the adjacent side wall 85 of the bracket 58, in which position said jaw 80' is slightly inclined with respect to its companion jaw so that said jaws permit the unobstructed gravity discharge of a buckle from the rack 60 into the track 78, but clamp a buckle on its advance movement in said track and particularly when it is at the assembly station A.

Pivotedly mounted at 90 on opposite sides of the block 24 are the legs 92 of a U-shaped stop 94 (Figs. 1, 4 and 5), the yoke 96 of which has a bevelled surface 98 (Fig. 3) that terminates in a lip 100. The stop 94 is normally urged by springs 102 into the operative position shown in Fig. 3, in which bevelled surfaces 106 on the legs 92 of said stop engage the correspondingly bevelled ends 108 of the projecting legs 26 of the block 24 in the fashion shown in Fig. 3. The springs 102 are anchored at 104 on the legs 26 of the block 24 (see also Fig. 4). In the operative position of the stop 94 (Fig. 3), its lip 100 projects into the confines of the track 78 and serves to prevent backward or reverse movement in said track of a buckle at the assembly station. The foremost end of the slide 32 is also bevelled as at 110 (Figs. 1 and 3) and is adapted, during an advance or feed stock of the slide, to cooperate with the bevelled surface 98 of the yielding stop 94 and cam the latter out of the path of forward movement of said slide and of a buckle being transferred thereby in the track 78. As soon as a buckle 62 has been advanced by the slide 32 in the track 78 to the assembly station A therein (Figs. 2 and 3), the lip 100 of the yielding stop 94 will, on being cleared by the retracting slide 32, project into the track 78 and prevent backward movement of the advanced buckle in the track 78 from the assembly station A. The stop 94 is preferably provided with a lug 109 (Figs. 1 and 2) which, in the operative position of said stop, prevents spreading of the jaws 80 to an extent where a buckle therebetween at the assembly station A could drop out or be removed therefrom in a direction laterally of the plane of said buckle.

Suitably mounted at 110 on the base 20 of the apparatus is a pedestal 112 having lateral arms 114 in which parallel rods 116 and 118 are slidably mounted. The upper ends of the rods 116, 118

are operatively connected by a cross member 119. Rod 118 carries at its lower end blades 120 and 122, which are adapted to interlace or interloop tapes with a buckle 62 at the assembly station A (Fig. 2). The other rod 116 is connected by a link 124 with a foot pedal (not shown), and is normally urged by a compression spring 126 into the uppermost position shown in Fig. 1 in which an adjustable collar 128 on said rod 116 engages one of the arms 114 of the pedestal 112. On depression of the proper foot pedal by the operator of the apparatus, the blades 120 and 122 on the rod 118 are lowered through intermediation of the parts 124, 116 and 119, and perform their designated operations to be described hereinafter.

In using the present apparatus, the slide 32 is first advanced for the transfer of a buckle 62 from the rack 60 to the assembly station A in the track 78 (Fig. 2), as previously described. The shorter one (130) of two tapes 130 and 132 is then held by hand between the buckle 62' at the assembly station A and the raised blades 120, 122. The blade-carrying rod 118 is then lowered, by foot pedal action as explained, into its lowermost position, whereby the blade 120 threads the tape 130 through the aligned slot 64a of the buckle 62' as shown in full lines in Fig. 8. The tape thus threaded through the buckle is then folded into overlapping relation at its ends and impaled on a pin 134 which, as shown in Fig. 1, may be an open safety pin carried by a suitable holder 136 which may be of the type shown and described in the Alfandre et al., Patent No. 2,267,675, dated December 23, 1941. The pin holder 136 is preferably clamped to the base 20 of the apparatus by a screw 138 which extends through a longitudinal slot 140 in said holder 136, wherefore the latter is adjustable on the base 20 rotatably as well as longitudinally. The pin holder 136 is preferably so adjusted that the tape 130, when impaled on the pin 134, is held away from the buckle 62' in the fashion shown in Fig. 9, so as to be out of the path of the blades 120 and 122 for the interlacing of the longer tape 132 with the buckle 62'.

For interlacing the longer tape 132 with the buckle 62', the blade-carrying rod 118 is, after its first descent, held in the lowermost position shown in Fig. 8 in which a notch 142 in the blade 120 is below the buckle 62'. While the rod 118 is thus held in its lowermost position, the tape 132 is near one end thereof projected by hand into the notch 142 of the blade 120 in the manner shown by dot-and-dash lines 132a in Fig. 9, whereupon the rod 118 is permitted to spring-return to its uppermost position. When the rod 118 is thus retracted from its lowermost position, the notch 142 in the blade 120 takes the tape 132 along and passes it through the slot 64a of the buckle 62' in the manner shown in full lines in Fig. 9. The end of the tape 132 thus passed through the buckle 62' is then turned over into the dot-and-dash line position 132b in Fig. 9, i. e., into the path of the blade 122. The blade-carrying rod 118 is thereupon lowered as before, whereby the descending blade 122 passes the tape end 132b through the aligned slot 64b in the buckle 62' in the fashion shown in Fig. 10. The blade-carrying rod 118 is then permitted to spring-return to its uppermost position, and the superposed portions of the tape 132 at the buckle 62' (Fig. 10) are then grasped by the operator and inserted edgewise of said buckle through the transverse slot 68 into the communicating slot 64c in said buckle (Fig. 11). This finishes

the assembly of the buckle with the tapes (Fig. 12), and the buckle is then withdrawn forwardly from between the jaws 80 and the assembled strap left hanging from the pin 134 on which subsequently assembled straps will be left hanging until the pin holds a predetermined number of these straps. The loaded pin 134 is thereupon closed and removed from the holder 136, and an empty pin inserted therein for the reception of subsequently assembled straps.

As shown in Figs. 1 and 2, the tape-threading blades 120 and 122 extend with their planes longitudinally of the apparatus, i. e., face with their side edges toward the operator of the apparatus who is in front of the apparatus. Accordingly, the buckles 62 are so stacked in the rack 60 and transferred to the assembly station A that their elongated slots 64 extend with their longitudinal axes longitudinally of the apparatus. In thus presenting the buckles at the assembly station A, the operator has, by viewing the tapes in profile during their assembly with the buckles Figs. (8 to 11), maximum visual control over the disposition of said tapes, thus greatly facilitating the handling of the tapes for their assembly with the buckles. In order to permit the insertion of the superposed ends of a tape 132 (Fig. 10) into the slot 64 of a buckle at the assembly station edgewise of said buckle (Fig. 11), the jaw 80 adjacent the slotted side of said buckle terminates short of the transverse slot 68 in the latter, as is clearly shown in Fig. 2.

While I have shown and described the preferred embodiment of my invention, it will be understood that various changes may be made without departing from the underlying idea or principles of the invention within the scope of the appended claims.

Having thus described my invention, what I claim and desire to secure by Letters Patent is:

1. In buckle-and-strap assembling apparatus having a track leading to an assembly station and means for advancing a buckle in said track to said assembly station, a retractile stop normally projecting into said track in such close proximity to said assembly station as to back a buckle at said station and thereby prevent retraction of said buckle in said track from said station.

2. In buckle-and-strap assembling apparatus having a buckle supply magazine and a track leading from said magazine to an assembly station, means for transferring a buckle from said magazine into said track and advancing it in the latter to said assembly station, and a retractile stop normally projecting into said track in such close proximity to said assembly station as to back a buckle at said station and thereby prevent retraction of said buckle in said track from said station.

3. In buckle-and-strap assembling apparatus, having a buckle supply magazine and a track leading from said magazine to an assembly station, a reciprocable slide for transferring a buckle from said magazine into said track and advancing it in the latter to said assembly station, a movable stop normally projecting into said track in such close proximity to said assembly station as to back a buckle at said station and thereby prevent retraction of said buckle in said track from said station and means moving with said slide for moving said stop out of the path of a buckle being advanced in said track to said assembly station.

4. In buckle-and-strap assembling apparatus,

having a buckle supply magazine, a track leading from said magazine to an assembly station, and a reciprocable slide for transferring a buckle from said magazine into said track and advancing it in the latter to said assembly station, a stop normally yieldingly projecting into said track in such close proximity to said assembly station as to back a buckle at said station and thereby prevent retraction of said buckle in said track from said station, said stop being urged by said slide out of the path of a buckle being advanced in said track.

5. In buckle-and-strap assembling apparatus, having a buckle supply magazine, a track leading from said magazine to an assembly station, and a reciprocable slide for transferring a buckle from said magazine into said track and advancing it in the latter to said assembly station, a stop having a cam surface and being normally yieldingly projected into said track to prevent reverse movement therein of a buckle from said assembly station, said slide having also a cam surface cooperating with that of said stop to urge the latter out of the path of a buckle being transferred in said track.

6. In buckle-and-strap assembling apparatus, having a buckle supply magazine, a track leading from said magazine to an assembly station, and a reciprocable slide for transferring a buckle from said magazine into said track and advancing it in the latter to said assembly station, a yielding stop having a beveled end normally projecting into said track to prevent reverse movement therein of a buckle from said assembly station, said slide having a beveled surface outside said track and forwardly of a buckle being transferred adapted to cooperate with said beveled end of the stop to urge the latter out of said track on each transfer stroke of said slide.

7. A magazine for flat parts each having an opening and a slot narrower than said opening leading from the latter to the periphery of the part, comprising a rail projecting into the slots and openings of a stack of said parts to hold them in superposed relation and properly orient them with respect to each other, said rail projecting through the slots of the stacked parts to the outside of the latter, and a mounting for said rail to which the projecting rail portion outside the stacked parts is attached.

8. Transfer mechanism for flat parts each having a peripheral notch of varying width with a narrow portion thereof nearer the periphery of the part than a wider portion, comprising a track, a rack of substantially the cross-sectional contour of said notch and slidably fitting the notches of a stack of said parts to hold the latter in superposed relation, said rack projecting through the notches of the stacked parts thereon to the outside of the latter, a mounting for said rack to which the projecting rack portion outside the stacked parts is attached for disposing said rack in position to lead the stacked parts thereon into said track, and means for advancing a part in said track.

9. Transfer mechanism for flat parts each having a peripheral notch of varying width with a narrow portion thereof nearer the periphery of the part than a wider portion, comprising a track, a rack of substantially the cross-sectional contour of said notch and slidably fitting the notches of a stack of said parts to hold the latter in superposed relation, said rack projecting through the notches of the stacked parts thereon to the

outside of the latter, a mounting for said rack at one side of said track to which the projecting rack portion outside the stacked parts is attached for disposing said rack within the confines of said track in position to lead the stacked parts into said track, and means for advancing a part in said track.

10. In apparatus for assembling a strap and a buckle having an opening and a slot narrower than said opening leading from the latter to the buckle periphery, the combination of a track leading to an assembly station, a rail projecting into the slots and openings of a stack of said buckles to hold the latter in superposed relation, said rail projecting through the slots of the stacked buckles thereon to the outside of the latter, a mounting for said rail at one side of said track to which the projecting rail portion outside the stacked buckles is attached for disposing said rail within the confines of said track in position to lead the stacked buckles into said track, and means for advancing a buckle in said track to said assembly station.

11. In apparatus for assembling a strap and a buckle having a strap-receiving opening and a slot leading from the latter to the buckle periphery, companion jaws for releasably holding a buckle with the slot thereof facing one of said jaws, said one jaw being constructed to expose the slot in said buckle to admit a strap edgewise of said buckle through the slot thereof into the opening therein.

12. In apparatus for assembling a strap and a buckle having a strap-receiving opening and a slot leading from the latter to the buckle periphery, opposite jaws for releasably holding a buckle with the slot thereof facing one of said jaws, said one jaw terminating short of the slot in said buckle to admit a strap edgewise of the buckle through the slot thereof into the opening therein.

13. In apparatus for assembling a strap and a buckle having a strap-receiving opening and a slot leading from the latter to the buckle periphery, opposite jaws for releasably holding a buckle with the slot thereof facing one of said jaws, and a stop projecting between said jaws for locating said buckle in said jaws, said one jaw terminating short of the slot in the located buckle to admit a strap edgewise of said buckle through the slot thereof into the opening therein.

14. In apparatus for assembling a strap and a buckle having a peripheral notch, opposite jaws for releasably holding a buckle at an assembly station, and means for delivering a buckle from a supply to said jaws so that the notch in said buckle faces one of said jaws, said one jaw terminating short of the notch in a buckle at said assembly station to admit a strap edgewise of the buckle into the notch thereof.

15. Apparatus for assembling a strap and a buckle having a strap-receiving slot and a peripheral notch, comprising opposite jaws for releasably holding a buckle at an assembly station, means for delivering a buckle from a supply to said jaws so that the notch in said buckle faces one of said jaws, said one jaw terminating short of the notch in a buckle at said assembly station to admit a strap edgewise of said buckle into the notch thereof, and means for passing a strap through the slot in a buckle at said assembly station.

16. Assembling apparatus as set forth in claim 15, in which said jaws are relatively yielding to grip a buckle therebetween.

17. In apparatus for assembling a strap and a buckle having a peripheral notch, opposite jaws for releasably holding a buckle at an assembly station, a magazine for holding a multiplicity of buckles in stacked relation and including means for orienting said buckles so that their notches face in the same direction, and means for transferring buckles from said magazine to said jaws so that their notches face one of said jaws, said one jaw terminating short of the notch of a buckle at said assembly station to admit a strap edgewise of said buckle into the notch thereof.

18. Apparatus for assembling a strap and a buckle having a slot and a peripheral notch, comprising a track for buckles having opposite guideways leading to an assembly station, a magazine remote from said assembly station holding a stack of superposed buckles and leading them into said track, said magazine including means for orienting said buckles so that their notches face one of said guideways, said guideways holding a buckle at said assembly station and said one guideway terminating short of the notch of a buckle at said discharge station to admit a strap edgewise of said buckle into the notch thereof, means for transferring a buckle from said magazine into said track and advancing it in the latter to said assembly station, and means for passing a strap through the slot of a buckle at said assembly station.

HARRY ALFANDRE.
